UNITED STATES PATENT OFFICE.

CHARLES E. DULIN, OF SANDY HILL, NEW YORK, ASSIGNOR TO UNION PAPER BAG MACHINE COMPANY, OF PHILADELPHIA, PENNSYLVANIA, A CORPORATION OF PENNSYLVANIA.

ENVELOP-MACHINE.

No. 850,879.

Specification of Letters Patent.

Patented April 16, 1907.

Application filed November 5, 1901. Serial No. 81,166.

To all whom it may concern:

Be it known that I, CHARLES E. DULIN, a citizen of the United States of America, residing in Sandy Hill, in the county of Washington and State of New York, have invented certain new and useful Improvements in Envelop-Machines, of which the following is a true and exact description, reference being had to the accompanying drawings, which 10 form a part thereof.

My invention relates to machinery for manufacturing envelopes from a continuously-fed strip of paper, and has for its object to provide for the rapid and efficient manufacture of a peculiar style of envelop.

The nature of my improvements will be best understood as described in connection with the drawings in which they are illustrated, and in which—

20 Figure 1 is a plan view of the machine; Fig. 2, a side elevation with the belt-wheels on the main driving-shaft removed; Fig. 2^a, front elevations of certain rolls forming a detail of the machine. Fig. 3 is a sectional elevation through the operative parts of the machine, taken on the line 3 3 of Fig. 1. Fig. 4 is a plan view of the table upon which the web of paper is severed into lengths to be formed into envelopes. Fig. 5 is an inverted 25 view of the oscillating cutter used to sever the blanks in connection with the table of Fig. 4. Fig. 6 is a longitudinal section through the cutter and table, taken as on the line 6 6 of Fig. 5, showing the cutter in elevated position. Fig. 7 is a similar sectional view showing the cutter in depressed position. Fig. 8 is a sectional view similar to that shown in Fig. 3, showing the knife in 30 depressed position. Fig. 9 is a top view of the oscillating cutter. Fig. 10 is a side view of the stripper attached to the cutter, taken as on the line 10 10 of Fig. 9. Fig. 11 is a plan view of the stripper. Fig. 12 is a plan view of the edge-folding device; Fig. 13, a similar view of the upper part of the said device; Fig. 14, a side elevation of the said upper part. Fig. 15 is a plan view of the lower part of the fold-forming device; Fig. 16, a longitudinal section thereof, taken on the line 45 16 16 of Fig. 15. Fig. 17 is a cross-section through the fold-forming device assembled, taken on the line 17 17 of Fig. 13; Fig. 18, a similar cross-section taken as on the line 18

18 of Fig. 15. Fig. 19 is a rear elevation of the active parts of the machine with the 55 paste-box and the paste-wheel working in said box removed. Fig. 20 is a sectional elevation of the pasting and creasing rolls, taken as on the line 20 20 of Fig. 19 and showing the rolls in the act of forming the 60 crease. Fig. 21 is a similar view showing the operation of forming the final fold in the envelop. Fig. 22 is a detached view showing the construction of the cam P³; Fig. 23, a detached view showing the construction of the 65 cam O³; Fig. 24, a detached view showing the actual operation of the creasing-blades upon the blank. Fig. 25 is a cross-section through the trimming-rolls, taken as on the line 25 25 of Fig. 26. Fig. 26 is a front view of the 70 trimming-rolls. Figs. 27 and 28 are sectional views of the trimming-rolls, showing their operation upon the sections of the paper strip. Fig. 29 is a plan view of the strip, showing the cuts made upon it in converting it 75 into blanks to be manufactured into envelopes. Fig. 30 is a view of the blank; Fig. 31, a view of the blank with its edges turned in and pasted, and Fig. 32 a view of the complete envelop.

A indicates the frame of the machine, B the shaft-supporting cones B', upon which in turn the roll of paper (indicated at t) is supported. From this roll the paper strip P is shown as leading upward over guide-rolls B² 85 and B³ to the first pair of feed and slitting rolls, (indicated at D² C⁷), the said roll C⁷ being secured on the main driving-shaft C of the machine, to which are also secured fast and loose pulleys C' and C², a hand-wheel C³, 90 a gear-wheel C⁴, which engages a gear-wheel D⁸ on the shaft D, to which is secured the upper feed-roll D². This upper feed-roll is, as shown, grooved at D³ D³, and the lower feed-roll C⁷ is provided with projecting knives C⁸, 95 which extend into these grooves and which slit the paper on the lines T⁴ T⁴ of Fig. 29. The shaft C has also attached to it a cam (indicated at C⁶) and a second gear-wheel, (indicated at C⁵), which through an intermediate 100 gear c⁵ (see Fig. 1) communicates motion to a gear G', secured to the shaft G, to which shaft is secured a gear-wheel G², driving through the gear-wheel H' the shaft H, and also a third gear-wheel G³, which communicates 105 motion through the intermediate gear g' to

the shaft I through its gear-wheel I' and to the shaft L through its gear-wheel L', said gear-wheel L' in turn actuating the shaft M through its gear M'. The gear-wheel G', before mentioned, in turn communicates motion through an intermediate gear-wheel g^x to the shaft O, through its gear O', and this shaft in turn is provided with a gear-wheel which engages the gear-wheel P', secured to the shaft P, the said gear-wheel P' also engaging and driving a shaft Q through its gear q. All of the above parts, it will be observed, are positively and constantly in motion.

Returning now to the operative part of the machine, the slitting and feed rolls on the shaft C and D slit and deliver the paper over the table E, which near its upper end, is formed with an upwardly-extending shoulder E', said shoulder supporting a knife-edge e' and a backwardly-extending receiving-plate, (indicated at e².) while the table proper, E, is shown as covered by a thin plate e and near its bottom edge is provided with lateral guide-blades, (indicated at E² E².) Extending across the table and supported in suitable bearings is the rock-shaft F of the oscillatory cutter, having attached to it a lever F', which is held in contact with the cam C⁶ by the action of a spring F². As shown, the rock-shaft F is cut away, flattened, and somewhat extended at the center, as indicated at f, and to the under side of this flattened portion is secured what is, preferably as shown, a circular knife F³, having a downwardly-extending cutting edge (indicated at f³) and secured to the oscillatory shaft by a central bolt, (indicated at F⁵.) This circular construction of the knife enables it to be angularly adjusted and fresh cutting edges brought into operation. Also secured to the flattened portion of the oscillatory shaft are the cutters or knives F⁴, having sharp cutting edges f⁴ fitting against the opposite sides of the circular knife F³. Extending close to the face of the knife F³ and between the cutters F⁴ is the stripper-plate F⁶, having its front end preferably bent slightly upward, as indicated at f⁶. This stripper-plate is by means of upwardly-extending pins and springs F⁹ secured to fingers F⁸, extending out from the flattened portion f of the shaft, the springs holding the stripper normally flush with the knife-edge to permit it to move upward when necessary. The shape of the stationary cutter e' is shown in Fig. 4 and corresponds to the cutters F⁴ and the portion of the circular cutter F³ lying between these stationary cutters. The strip of paper is fed over the table E, and when a determined length has been fed forward the cam C⁶, acting on the arm F', causes the rock-shaft F to move downward from the position shown in Fig. 6 to that shown in Fig. 7, severing the paper on the lines T' T², as indicated in Fig. 29, the stripper F⁶ hold-

ing the end of the strip against the top of the cutter e', while the knives press the severed portion of the strip down to the surface of the plate E.

The elastic stripper, while holding the end of the strip against the top of the cutter e', as described, prevents it from moving forward; but the feed-rolls are in constant operation, and there is consequently a slack formed between the feed-rolls and the stripper; but as soon as the upward movement of the knife, carrying with it the stripper, disengages the edge of the paper the elasticity of the paper causes it to spring forward, taking up the slack, so that the machine operates exactly as though there were no interruption in its feed.

Before the paper is severed, as above described, its forward end, passing between the guides E², has come between the rolls H² and G⁴, which rolls are secured on the shafts H and G and act partly as feed-rolls and partly as trimming-rolls. The lower roll G⁴ has a copper center, on each side of which are rawhide extensions, (indicated at G⁵ G⁵, see Fig. 26,) and from these rawhide extensions extend pins, (indicated at G⁶ G⁶.) The upper roll H² is made in three sections, the outer ones being indicated at h² h² and the inner one being angularly adjustable on the shaft. To the outer section h² of the roll are secured the knives H⁴ H⁴, which make the cuts indicated at T³ T³ in Fig. 29, the operation of the rolls H² and G⁴ being to sever from the blank the strips indicated at T' T' in Fig. 29 and complete the formation of the blank, as shown in Fig. 30.

As the blank is fed from the table E to the rolls G⁴ and H² it is pressed down over the pins G⁶, which pass into the grooves between the roll-sections H² and h² and which hold the strips T' to the face of the roll G⁴ as they are cut off from the blank, as shown in Fig. 26. These strips T' are finally stripped from the roll G⁴ by the action of stripping-fingers G⁷. (Shown in action in Fig. 28.) The blanks next pass to the edge-folding mechanism, being delivered from the rolls H² G⁴ over the guide-fingers J⁴ J⁴ to the folding mechanism (best shown in Figs. 12 to 18) and consisting of a lower plate J, to which the fingers J⁴ are attached and which is formed with side walls of plowshare-like character) indicated at J' J' merging into substantially vertical walls J². Between these walls of the plates J is placed the folder portion K, having walls K², also of a plowshare-like character, which act to turn the edges of the paper blank downward over a thin plate K³, which is secured to the bottom of the portion K and the front end of which projects forward and turns slightly upward, as indicated. To the rear end of the portion K are secured the presser-fingers K⁴ K⁵, which act upon the folds after they leave the folding device and compact

them into more permanent shape, the action of this folding device being to fold over, on the lines $T^7 T^7$ the projecting edges $T^8 T^8$ of the blank, as shown in Fig. 31. To facilitate the feeding of the blanks through the edge-folding devices described, I have shown the rolls $I^2 i^2$, which extend through the openings J^3 and K^4 in the lower fold-forming device J and the thin plate K^3 . The roll I^2 is secured on the shaft I , and the roll i^2 on the shaft i , which is not positively driven, but rests with simply its weight upon the paper and, through the paper, upon the roller I^2 . In order to balance the narrow rollers $I^2 i^2$, I provide the shafts $I i$ with balancing-rolls $I^3 i^3$, as shown in Fig. 2^a.

From the edge-folding mechanism the blanks pass between feed-rolls L^2 and M^2 on the shafts L and M and are fed over the guide-plate N to the pasting and creasing rolls to be described. As shown, the roll M^2 , which is a narrow one, is formed with a flattened portion M^3 , which relaxes the grip of the rolls on the blanks after they are engaged by the creasing device on the succeeding pair of rolls. The presser-fingers K^5 , as shown, act upon the surface of the lower roll L^2 .

To the shaft O is secured a roll O^4 , having grooves formed in it, as shown at $O^5 O^6$, and set across its face a block O^4 , (best shown in Fig. 24,) having formed along its face a cavity forming at its base a bearing for a shaft O^{10} , from which shaft extends up into the cavity the creasing-blade O^9 . The shaft O^{10} (see Fig. 19) has attached to its end a crank arm or lever O^{11} , carrying a cam-roller O^{12} , which by a spring O^{13} is held against the face of the cam O^3 , which cam is secured on a sleeve O^6 , supported on the shaft O and angularly adjustable thereon by means of its segmental extension O^7 , (see Fig. 23,) having in it a slot O^8 , through which extends a bolt O^9 , (see Fig. 19,) securing it to the frame A .

It will be obvious that by adjusting the segment O^7 the action of the cam upon the arm of the cam-shaft will be varied. Secured to the shaft P , which is driven from the shaft O , are the sectional rolls $P^2 P^2$, acting against the face of the roller O^4 , and between which lies the sectional roll P^2 of smaller diameter. On the rolls P^2 are secured paste-applying segments (indicated at P^4) and the function of which is to apply lines of paste to the folded edges of the blank, as indicated in Fig. 31. The central roll P^2 is preferably cut away, as indicated at P^5 , and through this cut-away portion of this roll, as well as through the flanking-rolls, extends the shaft P^7 , (see Fig. 24,) to which is attached the creasing-blade P^6 , the shaft having attached to one end the crank-arm P^8 , supporting a roller P^9 , which by means of a spring P^{11} is held in contact with a fixed cam P^3 , secured around the shaft P , as shown in Figs. 19 and 22. The paste-applying segments P^4 run

in contact with the surface of the paste-wheel Q' , secured to the shaft Q and running in the paste-box Q^2 , Q^3 indicating the usual knife-blade of the paste-box, close to which the edge of the roller Q' runs. $R R$ are fingers, the front ends of which lie in the grooves O^5 of the roll O^4 , the said fingers being secured to a shaft R' , from which extend lever-arms R^2 , carrying their free ends rolls $R^3 R^3$, which are held against the face of the roller O^4 by the action of springs $R^4 R^4$. (Shown in Fig. 19.)

The blanks folded as shown in Fig. 31 pass over the guides N between the rolls on the shafts O and P and are engaged by the groove-forming plates on said rolls, as shown in Fig. 24, the paper being pressed down by the finger P^6 between the finger O^9 and the wall of the cavity, in which it operates along the line T^9 of the blank. The shape of the cam O^3 is such that the finger O^9 maintains its grip upon the crease as the creasing-fingers recede from each other, the finger P^6 being withdrawn from the crease and the creased fold carried downward into the bight of the rolls O^4 and R^3 , the front end of the blank T^{11} of the blank, which has been fed between guide-plates $N N$, (see Figs. 20 and 21,) being retracted therefrom and the blank folded gradually, as shown in Fig. 21, to the form shown in Fig. 32; but the paste-applying segments P^4 have applied lines of paste to the folded edges T^8 and completes the formation of the envelop, the completed envelop being stripped from the roller O^4 by the fingers $R R$, over which it passes, as shown in Fig. 21.

Certain features of invention shown and described, but not specifically claimed herein, are so claimed in my copending application, Serial No. 328,648, filed the 1st day of August, 1906, as a division of this application.

Having now described my invention, what I claim as new, and desire to secure by Letters Patent, is—

1. In an envelop-machine, the combination with mechanisms for severing lengths from a paper strip and trimming such lengths into the form of blanks having their front ends narrower than their rear ends, of flap-turning mechanism acting to fold the edges T^8 of the blank over on the part T^{10} as the blanks are fed through the machine, said mechanism consisting of a former having plowshare-like sides and a central thin plate lying between said sides and over which they turn the edges T^8 and fold pressing-fingers $K^6 K^5$, situated in the rear of the former and thin plate and acting to further define the folds of the edges.

2. In an envelop-machine, the combination with mechanisms for severing lengths from a paper strip and trimming such lengths into the form of blanks having their front

ends narrower than their rear ends, of flap-turning mechanism acting to fold the edges T^8 of the blank over on the part T^{10} as the blanks are fed through the machine, paster mechanism for applying lines of paste to the folded edges, a pair of creasing-rolls, acting after the edges are folded and pasted, said creasing-rolls being adapted to form the crease-line T^9 across the blank and feed-rollers subsequently acting to engage the blank at the crease-line T^9 and press the end T^{11} down on the folded and pasted edges T^8 .

3. In an envelop-machine the combination with mechanisms for severing lengths from a paper strip and trimming such lengths

into the form of blanks having their front ends narrower than their rear ends, of flap-turning mechanism acting to fold the edges T^8 of the blank over on the part T^{10} as the blanks are fed through the machine, paster and creasing rolls P^4 O^4 acting to apply lines of paste to the folded edges T^8 and to crease the blanks transversely on, the line T^9 and a feed-roller acting on the roll O^4 to engage the blanks at the crease and press the end T^{11} down on the folded and parted edges.
